UNITED STATES PATENT OFFICE.

GEORGE B. KELLY, OF BOSTON, AND J. HERBERT CHASE, OF CAMBRIDGE, MASSACHUSETTS.

MECHANICAL MUSICAL INSTRUMENT.

SPECIFICATION forming part of Letters Patent No. 241,993, dated May 24, 1881.

Application filed August 30, 1880. (Model.)

To all whom it may concern:

Be it known that we, GEORGE B. KELLY and J. HERBERT CHASE, respectively of Boston and Cambridge, in the counties of Suffolk and Middlesex and State of Massachusetts, have 5 invented certain new and useful Improvements in Mechanical Musical Instruments, of which the following is a full, clear, and exact description.

10 This invention relates to improvements in mechanical musical instruments in which valves to reeds, &c., are operated by levers through the perforated and unperforated portions of a sheet material caused to travel 15 through the instrument; and it consists of the construction and arrangement of a series of supplementary chambers in a detachable board located between the wind-chest and reed-chambers, of valves located in said chambers, and 20 of a swell-board to the reed-chambers having a free valve, the several parts being constructed and arranged for operation in combination with levers and a perforated strip of paper or other suitable sheet material, all substantially as 25 hereinafter more fully described.

In the accompanying plate of drawings this invention is illustrated, Figure 1 being a plan view of a mechanical musical instrument constructed according to this invention, but with 30 the perforated strip removed; Fig. 2, a longitudinal vertical section on line $x-x$, Fig. 1, with the perforated strip in position and with the valve closed; Fig. 3, a similar sectional view to Fig. 2, above the bellows, but with the valve open; Fig. 4, a horizontal section of the detachable board having the supplementary chambers formed therein; Fig. 5, a cross-section of same on line $y-y$, Fig. 4; Fig. 6, a longitudinal sectional view, and Fig. 7 a plan view, of the 35 under side of the swell-board; Figs. 8, 9, 10, and 11, detail sectional views of the valve, to be hereinafter more particularly referred to.

In the drawings, A represents the wind-chest, B the bellows, and C the exhausters of 45 the bellows, all supported by the uprights D. E is a board secured to the wind-chest A, which board makes one side of the wind-chest and is the usual action-board of reed-organs, and to which are secured the parts making the action,

reed-chambers, &c., as usual in reed-organs, the board being secured by screws a , so that it can be attached and detached as desired.

G is the reed-chamber above action-board E, and having located therein the reeds H. This 55 reed chamber G at its opening b is covered by a swell-board, J, hinged at c , which swell-board has on its under or inner side a free valve, K, adapted to operate in connection with an opening, d , in the swell-board.

L is the perforated strip of paper, which is caused to travel through the instrument by the feed-rolls M and N, to one, N, of which is attached the crank-arm O, by which to operate the same, and to which crank-arm or its shaft 65 the bellows are attached for operation in any suitable manner.

P are the operating-levers. Each lever P swings vertically on a pivot, f , in a groove, g , of a cross-bar, Q, above the board E, and at 70 its end l has a V-shaped projection, m , to enter the perforations in the strip L in line with it as it, the paper strip, travels through the instrument. The other end, n , of each lever P bears against the under shoulder, o , of the free 75 end of a spring-lever, R, hinged at p to the board E.

S is a board located in the wind-chest A and secured to the under side of the action-board E, and having on its upper side, cut out or 80 formed in any suitable manner, recesses or chambers T, which, when the board is secured in place to the action-board E, form the supplementary air-chambers communicating with the reed-chambers G through openings q in the 85 action-board, and by openings r with the wind-chest, as shown in Figs. 2 and 3. This board S is secured by screws s to the action-board E, as shown in the drawings, so that it can be attached to and detached from the same at 90 pleasure, which is easily accomplished after removing the action-board.

In the supplementary air-chamber T is a valve, U, hinged by a leather joint to the bottom of said chamber, its weight being sufficient to keep it to its seat over the opening r when not in operation.

A downwardly-projecting arm, t , of the

spring-lever R enters the chamber T through an opening, u, in action-board E, in position to bear upon the end v of the valve U.

The operation of the instrument is as follows: Inserting the end of the perforated paper strip between the feed-rolls M N, which end is preferably unperforated for a short distance therefrom, turn the feed-rolls, and the paper strip is then fed along to and between the board V, held by spring-arms W, and the levers P, which, by its unperforated portion, presses the ends l of the levers down, and raising the spring-levers R the valves U will then drop to their seats by their own weight, closing their respective openings. In the continued movement of the perforated strip, as a perforation comes over a projection, m, of one of the levers P it enters such perforation; the spring-lever R then, through its arm t, opens the valve U, as shown in Fig. 3, which causes the reed to sound, provided the bellows are properly operated therefor. As the unperforated portion comes over a projection, m, the valve is closed, as before described.

Each reed has a separate chamber, T, valve U, and spring-lever R, which are arranged in the same vertical plane, and a lever, P, the levers P being arranged to converge from their connection with the spring-levers to their pivotal points, as shown in Fig. 1, by which means a much narrower strip of paper can be used than otherwise.

In the operation of the instrument the most power to open the valve is required at the instant the valve begins to rise from its seat, as at such time the full pressure of the air from the reed-chambers, caused by the exhaustion of the air from the wind-chest by the operation of the bellows, is exerted; but immediately the valve commences to rise the air from the reed-chamber passes under the valve, to and through the opening into the wind-chest, reducing its pressure in the chamber T and neutralizing its pressure or effect on the valve, which then requires, to fully open it, only sufficient power or pressure to overcome its weight, which is really nominal, and to a certain extent it is assisted in such opening by the air as it passes through the chamber.

A board, S, located as shown, having chambers T, and arranged to be attached and detached, substantially as described, has many advantages. It is cheap, simple, and easily constructed and readily attached and detached at pleasure, and is very desirable in the manufacture of these instruments, as well as reed-organs generally.

The swell-board forms a chamber over the reeds, and is applied for the purpose of softening the tone of the reeds when being sounded, and applying to said swell-board a free valve, substantially as shown, gives to the air passing to the reeds, to sound them when the swell is closed, a tremulous motion, thereby produc-

ing a tremulous effect on the tone of the reeds, 65 all of which effects are automatic, and thus varying and pleasing effects are caused on the tone produced by the reeds as the swell-board is opened or closed and the free valve caused to operate in the closing of the swell-board. 70

As when operating the instrument the air-pressure in the chamber T holds the valve firmly to its seat its own weight is sufficient to so hold it at other times in readiness for operation. Thus a light, free, and easily-operating 75 valve is secured. If desired, however, a light spring can be used with it; but it is practical and preferable without such spring. As the valve commences to rise from its seat against the air-pressure, as above described, it can do 80 so on a long leverage and short fulcrum, thereby lessening the power required to start the valve from its seat, and afterward, before being fully opened, change to a shorter leverage and longer fulcrum, as then less power is required to continue its opening movement. A longer fulcrum is preferable then, also, for it insures a full uncovering of the opening under the valve for a free passage of the air from the reed-chamber. Such an arrangement of fulcra 90 is shown in Figs. 8, 9, and 10, where a' is the shorter fulcrum and b' the longer fulcrum, the valve commencing to rise on the fulcrum a' and opening fully on the fulcrum b'. In Fig. 11 the valve has a convex surface on its under 95 side, whereby the fulcrum is changing constantly from a short to a long one.

The board S can be secured in any suitable manner that will allow of its being attached and detached as desired.

Having thus described our invention, what we claim, and desire to secure by Letters Patent, is—

1. In a mechanical musical instrument, an independent and detachable board, S, located 105 in the wind-chest A, said board having a series of chambers, T, and openings r, in which chambers T are located valves U over said openings, said valves being held to their seats by the pressure of air from the reed-chambers 110 when operating the instrument, all substantially as and for the purpose described.

2. A valve, U, hinged by a flexible material, and having two fulcra, substantially as and for the purpose specified.

3. In combination with reed-chambers of a musical instrument, a swell-board having a free valve, K, applied thereto, substantially as and for the purpose specified.

In testimony whereof we have hereunto set 120 our hands in the presence of two subscribing witnesses.
